UNITED STATES PATENT OFFICE.

EDGAR ROUSE SUTCLIFFE, OF LEIGH, ENGLAND, ASSIGNOR TO PURE COAL BRICKETTES LIMITED, OF CARDIFF, WALES.

APPARATUS FOR DISTILLATION OF CARBONACEOUS SUBSTANCES.

Application filed May 13, 1918. Serial No. 234,277.

(GRANTED UNDER THE PROVISIONS OF THE ACT OF MARCH 3, 1921, 41 STAT. L., 1313.)

This invention relates to the destructive distillation of coal and similar carbonaceous substances and has for its object to secure economy and efficiency in applying heat by 5 means of heated gases passed through the charge to be distilled.

The invention is especially applicable in the destructive distillation of coal which has been reduced to a uniform condition of extreme fineness and compressed to produce stonelike blocks or pieces without the necessary use of a binder, by subjecting such blocks to a coking process, and in the employment of blocks for coking that are substantially non-expansible, but the invention is of general application to the destructive distillation of carbonaceous substances and for the treatment or reduction of ores and for similar purposes.

According to the invention in its application to the destructive distillation of coal, the distillation is effected continuously within a retort which is advantageously vertically disposed, the retort being divided into parts or zones whose position is determined by means of ports or sets of ports through which the heating gases respectively enter and leave the retort, so that thus the distillation mostly takes place in the main or middle part of the retort in a position between these respective ports or sets of ports, leaving a part or zone at the upper end, and a part or zone at the lower end. Into the part or zone at the upper end of the retort coal is fed and the process of distillation gradually commences in that part of the retort whereby the vapors and gases produced in the commencement of the distillation there pass directly through an outlet provided at the upper end of the retort, whereby a considerable part of the tar vapors and other bodies are removed on production without passing through the main or middle part of the retort.

At the lower end of the retort the partially or almost completely distilled charge accumulates and being retained so as to give off its remaining content of gas or volatile matter to the extent required under the heat already acquired, the charge slowly cooling in the lower part of the retort before

its discharge at the lower end thereof. By such means the charge is gradually cooled in the lower end of the retort where it is not subject to contact with the gases that traverse the main part of the retort, the gradual cooling serving the purpose of imparting to the carbonized residue a certain toughness and avoiding the necessity of the quenching of the coke on its discharge.

The coke may be continuously or intermittently fed into a receptacle at the lower part of the retort, while the coal is continuously or intermittently fed into the upper part thereof.

According to the invention, moreover, the retort is heated internally by means of gases which are produced by the combustion of gas within the blast stove or alternately by passing gas through the heated blast stove. Each retort or set of retorts is advantageously provided with two blast stoves or sets of blast stoves for alternate operation in periods for example of one-half hour, so that thus while one blast stove is being heated by the combustion of gas therein, the other blast stove which has previously been heated in a like manner has gas passed through the gas thus being heated and thence flowing through the retort continuously.

According to the invention the retort is advantageously provided as a vertical retort of large capacity divided into sections or zones in the manner described. At the upper end of the main or middle part of the retort ports are provided which respectively directly communicate with the upper ends of the adjacent blast stoves, while at the lower end of the main or middle section of the retort, ports are provided which directly communicate with the lower end of the blast stoves. At the upper part of each blast stove a nozzle or nozzles is or are provided through which gas may be passed into the blast stove, the nozzle or nozzles being so disposed as to have an injector-like action upon the gases and vapors in the retort whereby they are drawn from the upper end of the middle or main part of the retort, the gases from the retort being thus induced to circulate through the heated blast stove and being discharged from the blast stove into

the lower end of the main or middle part of the retort under the action of the injector nozzles referred to, whereby they are heated and discharged into the retort to maintain 5 the distillation of the charge.

It will be understood that valves or dampers are provided by which communication between the respective blast stoves and the retort may be cut off for alternate heating.

10 Air may be introduced into the respective blast stoves at the lower end thereof. The combustion gases would then pass upwardly through the blast stove and thence through an outlet flue at the upper part thereof.

15 The invention comprises the method and means hereinafter described.

The invention is illustrated in the accompanying drawings in which—

20 Figure 1 diagrammatically represents in vertical sectional elevation one constructional form.

Figure 2 diagrammatically represents a modification in a similar view.

25 In carrying the invention into effect according to one construction as illustrated diagrammatically in Figure 1 in its application to a single unit plant for the distillation of coal, I provide a setting comprising a vertical retort *a* which for example may 30 be of a height of 30 feet and of a cross-section 5 feet by 10 feet having two blast stoves *c*, *c*¹, disposed one on either side of the retort. The respective blast stoves *c*, *c*¹, have a height corresponding to the height of the 35 middle or main part of the retort and these blast stoves communicate at their upper and lower ends respectively with the ports *d*, *e*, provided at the upper and lower ends of the main or middle part of the retort in the manner hereinbefore described. At the upper 40 end a flue *f* is provided for each blast stove and nozzles *g* are provided therein in a position transversely to the flue *f*, while the blast stove *c* or *c*¹ is gradually constricted 45 at its upper part at which it communicates with this flue *f*, the nozzle or nozzles *g* being so disposed that on gas being passed therethrough the gases may be drawn from the retort *a* through the flue *f* into the blast 50 stove. Thus a circulation of gas is maintained.

When heating the blast stove *c* or *c*¹ the valve *e*¹ closing communication with the lower end of the middle or main part of the retort is closed and gas and air admitted to the lower part of the blast stove from the flue *i* through the valve *i*¹. The flue *f* at the upper end of the blast stove has its outlet valve *j* open and the valve *h* between the 60 upper part of the blast stove and the retort closed, so that thus the combustion gases pass through the flue *f* and upwardly through the outlet flue *f*¹. After one blast stove has been heated the valves of the respective blast stoves are reversed and cold 65

gas is then injected through the nozzle *g* into the upper part of the heated blast stove, while the cooled blast stove is then heated, the alternate heating of the respective blast stoves taking place at suitable periods.

70 The upper part of the retort is advantageously diverted to one side as at *k* and at that side the carbonaceous material is delivered thereto whereby it slides or falls down into the upper part of the retort. An outlet *l* is provided in the upper part of the retort as hereinbefore described through which gas and vapors may pass for condensation and purification, part of the gas produced being then utilized for heating the blast stoves and for heating the charge in the 75 retorts in the manner described.

80 At the bottom of the lower part of the retort *a* an inclined surface *m* is provided beneath the retort by means of which part of the weight of the charge may be supported, and this inclined surface may form part of a chute by which the charge may be directed into a movable receptacle into which the residue may periodically be discharged. At 85 the end of this inclined surface a hinged plate *n* may be provided adapted to be operated from the outside of the chute, so that it may be brought from a position in which it lies at right angles with the inclined surface and forms a stop to hold the charge, to a position in which it depends vertically from the lower edge of the inclined surface, so that the charge that lies upon the inclined surface may thus, being unsupported, 90 fall into the receptacle.

95 In the lower part of the retort steam or cold water gas may be injected for example through a nozzle *a*¹ with a view to the removal of the by-products as well as to cool 100 the charge.

105 It will be understood that the heating of the charge within the retort is effected entirely by the heated gas which may be coal gas, for example. The gas and vapor passing from the retort may for example be about 25,000 cubic feet per ton of coal. The gas returned to the respective blast stoves may be about 15,000 cubic feet per ton, while the gas actually burnt in the blast stoves 110 may be from 4,000 to 5,000 cubic feet. It will be understood that these figures are given by way of example only and to indicate the character of the method involved. The gas circulated through the blast stoves 115 per ton of coal would for example be from about 60,000 to 100,000 cubic feet per ton.

120 The gas and vapor from the upper part of the retort may not pass directly to the blast stove, but instead all the gases may first be taken away through the upper part of the retort and, after being cooled and washed by suitable means, passed into the regenerator.

125 In carrying the invention into effect as illustrated diagrammatically in Figure 2, a 130

series of retorts a of rectangular horizontal cross section are provided and adjacent or to the rear of each retort a blast stove c^2 is provided. The blast stove c^2 is heated by the admission of gas and air at c^3 . A valve o is provided to open for the outward passage of the waste gases on heating the blast stove by which they may pass to the adjacent chimney a^2 . A valve p is provided, through which, after the blast stove has been heated, gas may be passed from the return gas main q so that thus the gas may pass through the heated blast stove and enter the retort through the ports e at the lower end thereof. It will be understood that the gas on passing from the retort would pass on through the condensers and by-product plant for the recovery of tar and other bodies and would then pass into the base of the blast stove at c^3 where it would meet the requisite amount of air for combustion. The damper or valve o to the chimney being open the hot gases would circulate through the blast stove chamber and heat up the brickwork. The period required for heating the blast stove would be arranged according to circumstances. For example a half-hour interval might be allowed. After heating the blast stove the valve o would be closed as well as the valves admitting gas and air to the base of the blast stove at c^3 . Purified gas is now allowed to pass in through the valve p and this would circulate through the blast stove, becoming heated and entering at the ports e passing thence through the fuel in the retort to distill or carbonize it and out at the top through the valve a^4 and the stand pipe a^5 into the hydraulic main a^3 whence the gas passes through the gas main a^6 . The duration of this operation may be determined according to circumstances. The period may for example be one half-hour and the temperature of the blast stove may be regulated so that the temperature of the gases passing through the ports e into the retort may be determined according to the conditions of distillation. The temperature may for example be from 600 to 700° C. Where such an installation is intended more especially for the production of gas, the gas for heating the blast stove may be produced in a water-gas generator mounted adjacent the blast stove at the rear. The gas generator may be so arranged that the gas produced during the air blow would give a good producer gas for burning in the blast stove and for heating it to the required temperature. After termination of the blow and during the period when the gas is circulated through the generator, water-gas may be produced in the gas generator by so regulating the supply of steam that the period may be prolonged and this

water-gas is also turned into the base of the generator to pass through and mingle with the other gas passing through the ports e . By this system of working a proportion of water-gas, for example 40%, may be mixed with the gas and vapor coming from the fuel. At the same time the sensible heat in the water gas as well as that in the producer gas is fully utilized.

It is known that the passing of hot water-gas through hot coke has the effect of liberating nitrogen and thus of increasing the yield of ammonia but my object is also to assist in the liberation of the volatiles from the fuel in the retort. Instead of washing all the gas produced in the retort, the gas could be passed direct from the top of the retort through the blast stove and thus reduce the quantity that is required to be treated in the by-product plant.

It will be understood that as the fuel passes down the retort it is subjected to a gradually increasing temperature whereby the volatile constituents of the fuel are taken off at the temperature most suitable.

Means may be provided for a continual circulation of gas through the retort a . For this purpose gas could be taken from a point near the upper end of the retort and returned near the lower end of the retort where it is admitted through the ports e .

The invention is not limited to the destructive distillation of coal. It may be employed for applying heat to ores in their reduction or to metals for their treatment or for any other similar purpose.

In the employment of the invention for the reduction of ores, briquettes may be employed in which the necessary amount of fuel or coal may be incorporated with the ore.

Furthermore it will be understood that no limitation is involved to the temperatures employed in the distillation. The method employed is applicable for distillation at comparatively low or at comparatively high temperatures.

It will furthermore be understood that the invention is not limited to the actual methods of operation described. It is obvious that one set of blast stoves may be employed for more than one retort.

I claim:

An apparatus for the continuous distillation of carbonaceous substances by internal heating, comprising a distillation retort, two blast stoves for the said retort adapted for use alternately for the combustion therein of gas for heating the blast stove while heating gas used for the distillation is heated in the other blast stove and comprising an inlet under the control of a valve at the lower end of each blast stove for the alternate admission of gas and air for heating the blast stove, a flue between the bottom

of each blast stove and the retort, a flue at the upper end of each stove under the control of a valve for the outlet of the waste combustion gases, flues affording communication between the upper end of the respective blast stoves and the top of the retort under the control of valves, and noz-

zles at the upper end of the respective blast stoves so set that on the passage of gas through the nozzles, circulation of gas from the upper end of the retort downwardly through the blast stove is induced, substantially as described. 10

EDGAR ROUSE SUTCLIFFE.
